UNITED STATES PATENT OFFICE.

WILLIAM MILLS, OF BIRMINGHAM, ENGLAND.

PERCUSSION CAP, FUSE, AND THE LIKE FOR USE IN CONNECTION WITH GRENADES,
EXPLOSIVE MINES, AND OTHER LIKE APPARATUS.

1,182,582.

Specification of Letters Patent.

Patented May 9, 1916.

Application filed November 23, 1915. Serial No. 63,084.

To all whom it may concern:

Be it known that I, WILLIAM MILLS, a subject of the Kingdom of Great Britain, residing at Bridge street west, Birmingham, in the county of Warwick, England, engineer, have invented certain new and useful improvements in or relating to percussion caps, fuses, and the like for use in connection with grenades, explosive mines, and other like apparatus, of which the following is a specification.

This invention comprises certain improvements in or relating to percussion caps, fuses, and the like, for use in connection with grenades, explosive mines, and other like apparatus.

In connection with a fuse adapted to be fired or ignited by a percussion cap, and in which the extremity of the fuse is introduced into a housing or aperture in juxtaposition with the cap, the latter upon being fired is liable to create a pressure between the cap and the fuse and to blow, or tend to blow, the fuse, or the end thereof, out of the aperture or housing, or to create a pressure which is liable to burst the fuse at a position outside of the aperture or housing, this involving the possibility that the fuse, or the remaining part thereof, does not burn or continue to burn. Such a pressure is also liable in cases in which the fuse does burn, to shorten the period of burning of the fuse, as for instance by blowing through the interior of the latter. Thus the presence of this pressure is liable to result on the one hand in the detonator not being fired, and on the other hand in the detonator being fired too soon, in the first case with the result that the grenade does not explode, and in the second case with the result that considerable danger is involved in using the grenade.

The present invention comprises a particularly efficient and satisfactory mode of and means for relieving the pressure in the vicinity of the cap, this having the advantage that the fuse is effectively relieved from this pressure bodily and internally, and the products of combustion are enabled to escape.

The present invention further provides a construction or arrangement providing for the more effective and certain ignition of the time fuse by the percussion cap.

It is desirable that the extremity of the time fuse should not be disposed closely against the explosive part of the cap so that a space may be left between the explosive part of the cap and the fuse. According to the present invention, I make provision whereby the gases may escape by way of an aperture or passage through the explosive part of the percussion cap, that is to say in the case of a cap which is in the nature of a cylinder closed at one end by the explosive part and suitably mounted, the transverse part closing the cylinder, and which involves the explosive portion, is, instead of being in the nature of a transverse closure portion, in the nature of an internal annular flange, so that when this flange is struck the explosive gases are enabled to escape through the orifice or aperture which it encircles, and satisfactory firing of the fuse is thereby obtained.

The transverse part of the cap, and which may project externally to form a stop or shoulder by virtue of which the cap may be satisfactorily installed in a carrier part or anvil, may be of conical form, the outer face of the cap against which the striker operates being conical or concave and the explosive being contained within an annular space, the inner annular open mouth of which is thereby facing in an inclined direction the end of the fuse, so that while free escape of the gases is permitted, the flame of explosion is thrown toward the end of the fuse by reason of the disposal of the annular space in which the explosive is contained.

The means for insuring the provision of a space between the explosive part of the cap and the time fuse introduced into the cylindrical part of the cap or into a conduit or space in the vicinity of the explosive part of the cap, may be in the nature of a projection or projections adapted to project into the interior of the cylinder or space from the internal surface thereof, and the said projection or projections is or are advantageously of such form that they tend to guide or direct the flame of explosion of the percussion cap toward or against the central or combustible part of the time fuse.

In order that this invention may be clearly understood and readily carried into practice, reference may be had to the ap-

pended explanatory sheet of drawings upon which:—

Figure 1 is a sectional elevation of a grenade showing the present invention applied thereto. Fig. 2 is an enlarged sectional view illustrating one form of percussion cap according to the present invention, the cap being disposed within an anvil such as is shown in the grenade illustrated by Fig. 1. Fig. 3 illustrates a modified form of cap according to the present invention. Fig. 4 is a part front elevation and Fig. 5 is a part sectional side elevation of one form of striker according to the present invention. Fig. 6 is a sectional front elevation of a modified form of striker according to the present invention. Fig. 7 is a sectional front elevation of a still further modified form of striker according to the present invention.

In the drawings, and referring firstly to Fig. 1, *a* is a tubular housing in which a longitudinally moving striker *b* operates. Within one end of this tubular striker a separable anvil or cap plug *c* is adapted to be suitably secured. This anvil or cap plug is perforated axially and accommodates the cylindrical part of the cap. *d* is an externally disposed pivoted lever which engages with the head of the striker and normally retains it in its retracted condition, said lever *d* being normally retained in the position shown by a retaining pin incorporated at *e*. When it is desired to throw the grenade the pin at the position *e* is removed, the lever *d* being still retained in its same position by the hand grasping the grenade, and in the act of throwing the grenade the lever *d* is released and the striker is impelled by its spring and caused to strike the cap.

The percussion cap may be essentially in the nature of a cup member or member involving a cylindrical wall adapted to be inserted within the axial perforation in the anvil *c*. In the arrangement shown it is externally enlarged at both ends to engage with the respective faces of the anvil so that the cap is restrained from displacement in either direction. The cap may, however, be incorporated by other methods, and it need not necessarily involve the cylindrical extension. The time fuse *f* which is in the nature of a length of cord or tubular cordage internally containing the combustible material is adapted to be inserted at its one end into the open extremity of the percussion cap, or into the opening in the anvil. Positive stop means are incorporated for spacing the end of the fuse from the explosive part of the cap.

A plurality of projections *g* may be provided around the circumference of the space or cylinder, or a single annular projection *h* may be provided encircling the said space,

and this projection or these projections are advantageously arranged to function as a funnel or as parts of a funnel by which the flame of explosion is concentrated and directed to the central part of the fuse. 70 The projection or projections may be formed by inwardly denting the sheet metal wall of the cap; the dent or dents may be of shape corresponding with that of a ratchet tooth having a face at right angles to the wall of the cylinder, and against which face the end of the fuse is adapted to abut, and having an inclined face extending from the projecting extremity of this first-mentioned face obliquely toward the wall of the cylinder to form the inclined guiding portion above defined. The dents may be provided without breaking the metal of the cylindrical wall, or such metal of the wall may be formed with two longitudinal cuts so that 80 the inwardly projected part is in the nature of a bridge. Or, as shown in Fig. 1, the inwardly projecting part may be in the nature of an inclined tongue disconnected from the cylindrical wall at its projecting extremity, 90 and which tongue is cut from the wall and disposed in the position above defined for directing the flame of explosion to the central part of the fuse. Centrally within the percussion cap, that is to say in a position axially alined with the combustible contained in the part of the fuse which is inserted into the percussion cap or anvil, the vent *i* is provided adapted to vent the space between the explosive part of the percussion cap and the extremity of the fuse. The outer face of the cap may, as shown in Fig. 2, be substantially flat and may be provided with a slight inwardly depressed cone formation *j* around the central orifice. This conical formation around the central orifice may be more pronounced, and the entire face, or a substantial part of the face of the cap may be in the nature of a cone as shown in Fig. 3. As will be seen by this figure, the coning of the external perforated face of the cap in combination with the internal projection or projections, or the inclined guiding portions thereof, may be so incorporated as to result in the formation of a conical recess adapted to direct the flame to the central or combustible part of the fuse. The cap is suitably enlarged at *k* to rest upon the upper surface of the anvil, and such upper surface of the anvil may around the central perforation if desired be rounded off so that the shape of the anvil is adapted to the conical or other shape of the cap. 110

The striker is furnished with striking portions *l*, *l* adapted to engage with the part of the cap in which the explosive is contained, and the striker is centrally slotted or cut away, or otherwise left hollow or of such other form as to provide a free 120 passage for the escape of the gases issuing 130

from the central aperture or perforation in the explosive part of the cap. In one arrangement the two projections l , l adapted to strike the cap at diametrically opposite 5 points, are of such length that when they have struck and fired the cap they form distance members, by virtue of which a sufficient space is left between the face of the cap and the body of the striker, so that the 10 pressure gases, and other matters egressing by way of the vent can freely escape into the striker chamber. Alternatively or additionally, such striker is at a diameter at right angles to the diameter in which the 15 striking portions occur, furnished with a broad saw-cut m for a part of its length from its striking end; this saw-cut may extend entirely across the striker at its lower part, and may extend upwardly therefrom 20 in the form of grooves of depth gradually decreasing until they run into the surface of the reduced body of the striker, as shown in Fig. 4. Alternatively, the striker may be centrally drilled entirely or throughout 25 a part of its length, and in the latter case the striker is also drilled transversely to form in the striker a T conduit, the stem of the T being open at the face of the striker adjacent to the cap, as shown in Fig. 30 6. In a further alternative, we may drill the striker or the face thereof in the vicinity of the cap with an oblique perforation or conduit extending from this face and opening into the side of the striker, as 35 shown in Fig. 7. The escaping gases can thus enter the space around the body of the striker, from which space they may readily escape to the atmosphere. The arrangement is such that when the grenade is made, 40 and before it is to be used, the space in which the striker is contained may be sealed, as for instance by wax, this sealing being automatically broken upon the operation of the striker.

45 What I claim as my invention, and desire to secure by Letters Patent is:—

1. In ignition apparatus in combination, a percussion cap having an opening at one

end adapted to receive the end of a time fuse, said cap having a transverse portion 50 with a vent therein opposite said opening, a striker adapted to operate upon said transverse portion, said striker being of such character that when it contacts with the cap it does not close said vent provided 55 therein, and a stop for maintaining the end of the fuse in such position that it is spaced from the said transverse portion of the cap.

2. A percussion cap having an opening at one end adapted to receive the end of a 60 time fuse, said cap having a transverse portion opposite said opening, said transverse portion having an aperture therein for venting the cap, said transverse portion being designed to direct the flame of explosion 65 toward said opening.

3. A percussion cap comprising a transverse portion having a central vent, said transverse portion incorporating the explosive part of the cap and being dished inwardly 70 whereby the flame of explosion is directed inwardly.

4. In ignition apparatus in combination, a percussion cap, a time fuse adapted to be ignited thereby, and means for spacing the 75 time fuse from the explosive part of the cap, said spacing means being of a form adapted to direct the flame of explosion of the cap toward the central or combustible part of the time fuse. 80

5. A percussion cap comprising a body having an opening at one end for receiving the end of a time fuse and having a transverse portion opposite said opening, said transverse portion having a vent opening 85 therein and having an internal annular flange surrounding said vent opening for directing the flame toward said first mentioned opening.

In witness whereof I have hereunto set my hand in the presence of two witnesses.

WILLIAM MILLS.
